CLAIM

The ornamental design for a vacuum cleaner enclosure, as shown and described.

DESCRIPTION

FIG. 1 is a left front perspective view of the vacuum cleaner enclosure of this design;

FIG. 2 is a right side elevational view thereof;

FIG. 3 is a left side elevational view thereof;

FIG. 4 is a left rear perspective view thereof;

FIG. 5 is a bottom plan view of the vacuum cleaner enclosure of this design; and,

FIG. 6 is a left front perspective view, shown with the door in an open position.

The broken line showing is for illustrative purposes only and forms no part of the claimed design.
